AUTOMOBILE SEAT FOR CHILDREN

Isaac M. Goodrich, Colorado Springs, Colo.

Application March 1, 1954, Serial No. 29,275

Term of patent 14 years

(Cl. D15—1)

FIG. 1.

FIG. 2.

FIG. 3.

To all whom it may concern:

Be it known that I, Isaac M. Goodrich, a citizen of the United States, residing at Colorado Springs, county of El Paso, State of Colorado, have invented a new, original, and ornamental Design for an Automobile Seat for Children, of which the following is a specification, reference being had to the accompanying drawing, forming a part hereof.

Figure 1 is a side elevation of an automobile seat for children showing my new design;

Figure 2 is a front elevation thereof; and

Figure 3 is a rear elevation thereof.

I claim:

The ornamental design for an automobile seat for children, as shown.
